CLAIM

(60) Division of application No. 29/219,940, filed on Dec. 20, 2004, now Pat. No. Des. 529,254, which is a continuation-in-part of application No. 29/211,199, filed on Aug. 20, 2004, now Pat. No. Des. 528,258.

The ornamental design for a portion of a drawer of a service cart, as shown and described.

(51) **LOC (8) Cl.** **12-02**

DESCRIPTION

(52) **U.S. Cl.** **D34/27**

FIG. 1 is a perspective view of a portion of a drawer of a service cart of the present invention;

(58) **Field of Classification Search** D34/12, D34/14, 17, 19, 20, 21, 22, 23, 27; D6/396, D6/422, 510; D8/300, 301, 303, 313, 315; 312/198, 199, 200, 249.8, 249.11, 330.1

FIG. 2 is an enlarged perspective view of a part of the portion of a drawer of a service cart of FIG. 1;

See application file for complete search history.

FIG. 3 is another enlarged perspective view of a part of the portion of a drawer of a service cart of FIG. 1;

(56) **References Cited**

FIG. 4 is an enlarged fragmentary perspective view of a part of the portion of a drawer of a service cart of FIG. 1;

U.S. PATENT DOCUMENTS

FIG. 5 is a front elevation view of the portion of a drawer of a service cart of FIG. 1;
